UNITED STATES PATENT OFFICE

168,614

INTERCOMMUNICATING SYSTEM MASTER
STATION UNIT

James D. Floria, Fox Point, Wis., assigner to
Webster Electric Company, Racine, Wis., a cor-
poration of Delaware

Application July 27, 1951, Serial No. 16,051

Term of patent 14 years

(Cl. D26—14)

To all whom it may concern:

Be it known that I, James D. Floria, a citizen of the United States, residing at Fox Point, Milwaukee County, Wisconsin, have invented a new, original, and ornamental Design for an Intercommunicating System Master Station Unit, of which the following is a specification, reference being had to the accompanying drawing, forming a part hereof.

The single figure is a perspective view of an intercommunicating system master station unit embodying my new design.

The characteristic features of my new design are shown in full lines in the drawing. The left side and back of the unit are substantially plain.

I claim:

The ornamental design for an intercommunicating system master station unit, substantially as shown and described.

JAMES D. FLORIA.
